UNITED STATES PATENT OFFICE.

ALFRED H. WILLETT, OF WEST NEW YORK, NEW JERSEY, ASSIGNOR TO AMERICAN ARCH COMPANY, OF NEW YORK, N. Y., A CORPORATION OF DELAWARE.

WOOTEN-TYPE FIRE-BOX.

1,229,385.

Specification of Letters Patent. Patented June 12, 1917.

Application filed February 11, 1916. Serial No. 77,642.

To all whom it may concern:

Be it known that I, ALFRED H. WILLETT, a citizen of the United States, and a resident of West New York, county of Hudson, and 5 State of New Jersey, have invented certain new and useful Improvements in and for Wooten-Type Fire-Boxes, of which the following is a specification.

My invention relates to improvements in 10 locomotive boilers of the Wooten type which have firebox extensions within the barrel of the boiler forward of the grate.

The firebox of a Wooten type boiler differs from others chiefly in the matter of its 15 height. The distance between the grate and the crown sheet is much less than in locomotive fireboxes of other types. The reason of this peculiarity is that Wooten fireboxes are designed for use with anthracite coal; 20 a fuel which yields a very short flame, as compared with others, and which therefore necessitates the arrangement of the chief heating surface (the crown sheet) close to the fuel bed. The height of the firebox extension, sometimes called the "combustion 25 chamber extension", is determined by the height of the crown sheet, as in other fireboxes. Another characteristic of a Wooten firebox is that the grate is placed almost on 30 a level with the floor of the extension, and the throat sheet is extremely narrow.

It is claimed for the Wooten type firebox that by reason of its low height and narrow throat sheet there is a substantially 35 equal distribution of the hot gases in the flues of the boiler; and that this and the attendant easy maintenance of the flues and flue sheet, are advantages secured without material loss of heating value in the walls 40 of the firebox, inasmuch as the latter are close to the fuel bed. Against the admitted advantages of such fireboxes, I find that the flow of hot gases from grate to flues is so rapid and direct that the rear part of a 45 Wooten firebox is much less effective than supposed. And further I find that the use of the narrow throat sheet results in the piling of both fuel and ashes upon the floor of the firebox extension, and that the lower 50 flues of a Wooten firebox are more than often clogged and hence inefficient.

It has been suggested that a cure may be effected by providing Wooten fireboxes with inclined refractory arches of the kind used 55 in bituminous coal burning locomotives and

which in such locomotives have served to obviate disadvantages similar to those here mentioned as pertaining to Wooten fireboxes. But extensive experiments conducted in the past show that the lack of height 60 in the Wooten firebox, and its narrow throat sheet, prevent the practical and efficient use of an inclined arch of any of the ordinary kinds. Wooten fireboxes of the extension-type are therefore customarily used without 65 arches or baffle walls of any kind.

The object of my invention is to provide within a Wooten type firebox means which, in the absence of an inclined front arch, shall yet perform the chief well-known functions of such an arch. More particularly, the object of my invention is to provide a Wooten-type firebox with a wall of refractory material,—which during the operation of the firebox shall become practically incandescent and materially aid in both mixing and igniting the products from the burning fuel on the grate;—which shall prevent the direct flow of the products from the grate to the flues of the boiler, especially 70 the lower flues thereof;—which shall divide the firebox into a fire chamber substantially co-extensive with the grate, and a combustion chamber substantially co-extensive with the firebox extension;—which shall limit 75 communication between such chambers to an opening of an area substantially equaling the aggregate area of the flues;—which shall enforce the distribution of the hot gases upon all the walls of the fire chamber 80 and also cause the precipitation and collection of carried over ashes rearwardly of the flues;—which shall be of a construction that will permit it to be installed quickly and with little labor, and as quickly and easily 85 removed;—which shall be of low cost and very durable;—and which shall be of a form that will permit the easy removal of the ashes or cinders which collect in the combustion chamber.

The manner in which I attain the objects next above set forth, and the nature and particulars of my invention, will be understood on reference to the drawings that form part of this specification and in which;— 105 Figure 1 is a transverse section of a Wooten-type firebox embodying my invention;—Fig. 2 a longitudinal vertical section thereof;— Fig. 3 is a plan view of the top of the combustion wall;—Fig. 4 is a perspective view 110

of one of the wall sectors;—Fig. 5 is a perspective view of one of the two identical key bricks;—Fig. 6 is a perspective view thereof from the opposite position;—Fig. 7 shows a modified form of wall in which a key brick of different form is used;—Fig. 8 is another modification; and Fig. 9 illustrates a further modification of the invention.

10 The familiar parts of a Wooten type firebox are as follows:—the boiler-barrel, 2;—the firebox shell, 3;—the mud ring, 4;—the side sheets 5, 5;—the crown sheet, 6;—the rear sheet, 7;—side water legs, 8, 8;—the front water leg, 9;—the fuel door, 10;—and the throat sheet, 11;—the rear water leg, 12;—the so-called firebox extension, of which 13 is the floor;—the flue sheet, 14;—and, the flues, 15. The grate, 16, indicated by dotted lines, usually occupies the whole space within the confines of the mud ring, extending from side to side of the firebox and from the rear sheet, 7, to the throat sheet, 11. The firebox-extension is all that part of the firebox between the flue sheet, 14, and the throat sheet.

It will be noted that a Wooten firebox is of much less height than width. Instead of attempting to employ a refractory arch extending upwardly and rearwardly from the lower part of the throat sheet, 11, to divide the firebox into fire and combustion chambers, I employ for that purpose a vertical wall, A, composed of refractory bricks, and positioned in the firebox-extension. I place this wall on the floor, 13, of the firebox-extension and against the sides, 13', thereof. It extends substantially to the level of the greatest horizontal diameter of the firebox extension and divides the box into a fire-chamber, B, which is substantially co-extensive with the grate, 16, and a combustion chamber, C, that is wholly within the firebox extension. The opening, D, which remains between the top of the wall, A, and the crown sheet, 6, is preferably of a size to equal the aggregate areas of the many flues, 15.

As shown in Figs. 1, 7 and 9, I prefer that the lower part of the wall, A, shall contain an opening, A', the bottom of which is formed by the floor, 13, of the combustion chamber, C. The purpose of this opening is to permit the easy cleaning of the combustion chamber. The opening, A', may normally be closed by a number of small bricks, E, piled therein, as shown in Fig. 2. Such small bricks may be knocked out easily whenever it is necessary to gain access to the combustion chamber. But although, as stated, I prefer that the wall shall contain a clean-out opening, A', I nevertheless sometimes dispense with the opening and use an imperforate wall, as indicated in Fig. 8.

65 An upright refractory wall positioned as

here shown obviously prevents the flow of products from the fuel on the grate direct to the flues, 15, and more especially to the lower flues of the group. This function is, however, performed without detriment to the draft through the fuel, for under all conditions the draft is determined by the aggregate free area of the flues and, as the opening, D, is of substantially the same aggregate area, the draft conditions and varying vacuum in the chamber, B, remain substantially the same as though the wall, A, were not present. Though the wall does not lessen the draft, it nevertheless prevents the direct flow of the gases toward the lower flues and also has the effect of retaining the products of combustion in the fire chamber, B, for a longer time and in a state of better distribution upon the walls of that chamber.

As the gases pass through the opening, D, they attain their maximum velocity and on entering the larger chamber, C, their velocity is measurably reduced. In consequence, the ashes and cinders carried over by the swiftly moving gases from the chamber, B, are precipitated upon the floor, 13, of the chamber, C, and are thus prevented from entering the flues, 15.

The wall, A, of refractory material becomes substantially incandescent when the firebox is in operation and the heat thus continually stored in the wall greatly aids in the maintenance of substantially constant temperatures in the firebox and largely nullifies the bad effect of cold air admitted through the fuel door, 10. Further, the wall, A, baffles the flow of gases, as explained, and thereby causes the formation of conflicting currents in the chamber, B, and effects a better mixing of the combustibles and the certain ignition thereof in advance of their entrance to the chamber, C.

The heat in the firebox during operation is intense and I find that the cross wall cannot properly be constructed of small bricks; that is, a wall made of bricks of common size, such as the bricks, E, presents too many corners and surfaces to the attack of the flames and very quickly yields to the severe treatment to which it is subjected. Such a wall is therefore objectionable on the ground of lack of durability. A wall composed of small bricks is also objected to on the ground of expense. Too much time and labor are required in its construction. And such a wall does not well withstand the shocks to which it is subjected in a locomotive firebox. For these reasons I discard bricks of small size as the material for the cross wall, whether laid with or without mortar, and have invented a form of refractory wall which is composed of large, durable and stable elements or sections. These sections are preferably made in sizes as large as can be passed through the fuel door, 10. By

- means thereof a complete wall, A, may be erected in a very short space of time and without the service of a skilled mason.
- The lower part of a firebox extension is usually semi-cylindrical and I take advantage of this fact in the construction of my novel combustion wall. Instead of attempting to make the wall by piling bricks one upon another, I construct it of bricks which occupy radial positions in the lower part of the extension. In each case the wall is composed of a plurality of identical truncated sector bricks, in combination with one or more centrally disposed key bricks.
- Referring to Figs. 1, 3, 4, and 6, it will be noted that the wall is composed of six sector bricks, F, and two key bricks, G. All of the bricks, F, are of the same shape. Likewise, the key bricks are of the same form. In other words, the complete wall is composed of large bricks of only two different shapes. These bricks are of such size that they may freely pass through the fuel door opening, 10, of the firebox, and, though large and substantial, they are of such weight that they can be handled by one man. The bricks, F, are preferably not only identical in form but are identical in dimensions.
- As shown in Fig. 4, each brick, F, is a true truncated sector of a wall of a thickness shown in Fig. 3. On one side, the brick is provided with an interlocking groove, f, and on the other with an interlocking tongue or rib, f'. The base, f², is preferably curved to conform to the bottom of the firebox extension. In the base is a broad groove, f³, the purpose of which is to limit the contact of the base with the metal walls of the firebox and to provide space for the heads of the rivets belonging to the underlying seam, between the throat sheet of the extension. On the upper or small end of the brick, F, is an upstanding tongue, f⁴.
- When the several bricks are put together their tongues and grooves, f, f', serve to interlock them against relative movement, as indicated by dotted lines in Fig. 1.
- A single central or key brick may at times be substituted for the component bricks, G, G, of Fig. 1, provided only that the single brick shall be small enough to pass through the fuel door of the firebox. In most cases I prefer to make the key brick in two parts, G, G, as shown, and for the purpose of interlocking them I provide them with vertical tongues and grooves, g, g'. It should be understood that each brick, G, is provided with a tongue, g, and also with a groove, g', these being symmetrically arranged so that the groove of one brick will accommodate the tongue of the other. Thus made, any key brick, G, will interlock with any other key brick, G, said bricks being not only complementary, but also identical.
- I prefer in this manner to avoid the necessity for key bricks, G, of different shapes. The vertical faces, g², of the key bricks are thus substantially united when the bricks are placed together. The lower parts, g⁴, of the key bricks are used to separate or spread the two groups of bricks, F, and frame the top of the clean-out hole, A'. The upper parts, g⁵, of the bricks, G, rest against and upon the small ends of respective bricks, F, and contain peripheral grooves, g⁶, which interlock with the top tongues, f⁴, of the bricks, F. It is usually convenient to continue the grooves, g⁶, downward in the spreader portions of the bricks, G, as shown in Fig. 6.
- In constructing the wall, A, I usually place two bricks, F, with their ribbed sides innermost and assemble the key bricks, G, G, thereon, pushing the bricks firmly together. The remaining bricks, F, are then placed in position, from the top. The six bricks, F, and the two bricks, G, complete the wall; and when assembled, as shown, constitute a very rigid and substantial structure, adapted to long withstand both the heavy vibration of the locomotive and the intense heat of the fire.
- There are many cases in which I find it possible to make the clean-out opening, A', smaller than shown in Fig. 1. In such cases I dispense with the spreader portions of the key brick and use a key brick, H, of substantially semi-cylindrical form, as shown in Fig. 7. Two more sector bricks may be used in this case. The sector and key bricks, I and H, are interlocked by tongues and grooves, as before explained.
- In Fig. 9 I have illustrated a modified form of the invention in which the bricks are formed to provide a rectangular clean-out opening, A². Such an opening may be closed with small bricks, E, more readily than where the opening is of non-rectangular form. To accomplish this modification it is necessary to depart from the equilateral form for the sector bricks, for all of the sectors, J, should be modified in order that the innermost bricks may present the parallel vertical sides for the opening, A². The key bricks, K, K, are correspondingly modified in that their spreader portions, k, are of rectangular form. Such key bricks may be assembled with the bricks, J, somewhat more readily than the bricks, G (Fig. 1) and are no more difficult to interlock.
- A solid wall may be constructed in the form shown in Fig. 8 wherein all of the bricks, L, are true truncated sectors. The tops or inner ends of the bricks, L, are interlocked by means of a central key brick, M. To the end that it may be understood that the invention is not limited to interlocking tongues which are co-extensive with the sides of the sector bricks, I have shown

the bricks, L, provided with interrupted tongues and grooves, L'.

The sector and key bricks may fuse together more or less, but as individually they are very strong they may be separated without destruction. I count this a great advantage for it is often necessary to remove the wall and the expense of maintenance is greatly reduced by the ability to remove the 10 bricks intact and afterward reassemble them in their old relations.

Having thus described my invention, I claim as new and desire to secure by Letters Patent:—

- 15 1. A locomotive firebox having a combustion chamber extension forward of its grate and throat sheet, in combination with an upright refractory wall erected on the floor and against the sides of said extension, said wall being composed of a plurality of radially positioned sector bricks and a central key brick.
- 20 2. A locomotive firebox having a combustion chamber extension forward of its grate and throat sheet, in combination with an upright refractory wall erected on the floor and against the sides of said extension, said wall being composed of a plurality of radially positioned sector bricks and a central 25 key brick, and said key brick serving to interlock the sector bricks.
- 30 3. A locomotive firebox having a combustion chamber extension forward of its grate and throat sheet, in combination with an upright refractory wall erected on the floor and against the sides of said extension, said wall being composed of a plurality of radially positioned sector bricks and a central key brick, the latter comprising complementary 35 halves.
- 40 4. A locomotive firebox having a combustion chamber extension forward of its grate and throat sheet, in combination with an upright refractory wall erected on the floor and against the sides of said extension, said wall being composed of a plurality of radially positioned and interlocked sector bricks and a central key brick, the latter comprising complementary 45 interlocked halves.

5. A locomotive firebox having a combustion chamber extension forward of its grate and throat sheet, in combination with an upright refractory wall erected on the floor and against the sides of said extension, said wall being composed of a plurality of radially positioned sector bricks and a central key brick, the latter comprising complementary halves abutting on a vertical plane. 50

6. A locomotive firebox having a combustion chamber extension forward of its grate and throat sheet, in combination with an upright refractory wall erected on the floor and against the sides of said extension, said walls being composed of a plurality of radially positioned sector bricks and a central 55 key brick, the latter comprising complementary halves abutting on a vertical plane and including sector spreader portions. 60

7. A locomotive firebox having a combustion chamber extension forward of its grate and throat sheet, in combination with an upright refractory wall erected on the floor and against the sides of said extension, said wall being composed of a plurality of radially positioned sector bricks and a central 70 key brick having a sector spreader portion. 75

8. A locomotive firebox having a combustion chamber extension forward of its grate and throat sheet, in combination with an upright refractory wall erected on the floor and against the sides of said extension, said wall being composed of a plurality of radially positioned sector bricks and a central 80 interlocking brick, and said bricks being shaped to present a rectangular clean-out 85 opening in the lower part of the wall. 90

9. A locomotive firebox having a combustion chamber extension forward of its grate and throat sheet, in combination with an upright refractory wall erected on the floor and against the sides of said extension, said wall comprising a plurality of radially positioned truncated sector bricks, and a key brick interlocked with the truncated ends of 95 said sector bricks. 95

In testimony whereof, I have hereunto set my hand this 1st day of February, 1916.

ALFRED H. WILLETT.
